CONTROL FOR TWO-TEMPERATURE REFRIGERATORS

Walter M. Van Sciver, Lansdowne, and Raymond J. Ridge, Yeadon, Pa., assignors to Westinghouse Electric & Manufacturing Company, East Pittsburgh, Pa., a corporation of Pennsylvania

Application October 31, 1936, Serial No. 108,520
Renewed January 15, 1938

7 Claims. (Cl. 62—115)

Our invention relates to control systems for refrigerating apparatus having a plurality of zones to be refrigerated and has for an object to provide an improved system of this character.

5 A further object of our invention is to provide improved apparatus for controlling refrigeration of high and low temperature zones of a refrigerator wherein the high temperature zone is automatically refrigerated in preference to the low 10 temperature when both require refrigeration, with provisions for manually effecting refrigeration of the low temperature zone in preference to the higher temperature zone.

15 A still further object of the invention is to normally refrigerate the food storage chamber of a refrigerator in preference to the freezing chamber thereof and to manually effect, at will, refrigeration of the freezing chamber in preference to the food storage chamber with provisions for 20 establishing normal control of refrigeration of the chambers automatically in response to a predetermined temperature within the freezing chamber.

25 These and other objects are effected by our invention as will be apparent from the following description and claims, taken in connection with the accompanying drawing, forming a part of our application, in which:

30 The single figure of the drawing discloses, diagrammatically, a two temperature refrigerating system controlled in accordance with our invention.

35 Referring to the drawing, we show a two-temperature refrigerator generally indicated at 10, and including relatively high and low temperature chambers 11 and 12, respectively. Evaporators 13 and 14 are disposed within the respective chambers 11 and 12, for abstracting heat therefrom. The high temperature evaporator 13 operates, primarily, to cool articles of food stored in 40 the chamber 11 and the low temperature evaporator 14 operates to congeal fluid within containers shown at 15 and to maintain the temperature of the air in the chamber 12 at a relatively low value. Articles to be maintained in a frozen condition or at a low temperature are stored in 45 chamber 12 as is well understood.

50 The evaporators 13 and 14 define elements of a refrigerating system having a common condensing unit 15 and including a compressor 16 driven by an electric motor 17. The condensing unit 15 includes a condenser 18 cooled in any suitable manner as by a fan 19 and receives compressed refrigerant gas from the compressor through a conduit 21.

55 Liquid refrigerant is conveyed to the evapora-

tors 13 and 14 through a branched conduit 22 and vaporized refrigerant is withdrawn from the evaporators 13 and 14 through conduits 23 and 24, respectively. The refrigerating system which we have shown is of the well known flooded evaporator type having low side floats shown at 25 and 26 for controlling the admission of condensed refrigerant to the evaporators 13 and 14, in accordance with the levels of the liquid therein. A valve structure generally shown at 27 communicates with the suction conduits 23 and 24 and with the suction side of the compressor by means of a conduit 28. The valve structure 27 is selectively operated to effect communication between the conduit 28 and either conduit 23 and 24 depending upon which evaporator is being refrigerated.

As shown, the valve structure 27 includes inlet chambers 31 and 32 to which the suction conduits 23 and 24 are connected, and an outlet chamber 33 communicating with the suction conduit 28 of the compressor. Valve members 34 and 35 control communication between the chamber 31 or 32 and the outlet chamber 33. A solenoid 36 actuates the valve members 34 and 35 in such manner that, when the solenoid is energized, communication between the conduits 24 and 28 is established and the evaporator 14 is thereby rendered active. When the solenoid 26 is deenergized, the valves 34 and 35 move to their lowermost position or the position shown in the drawing and communication is established between the conduits 23 and 28 for rendering the evaporator 13 active.

During operation of the condensing unit 15, vaporized refrigerant is withdrawn by the compressor from either evaporator 13 or 14 through conduit 28 depending upon whether the solenoid 36 is energized or deenergized. The withdrawn gas is compressed to a relatively high pressure in the condenser 18 and is cooled and condensed. 40 Liquid refrigerant is admitted to the evaporators 13 and 14 through their associated float valves 25 and 26 and is maintained at a substantially constant level in the evaporators. The compressor maintains the pressure of the refrigerant in the 45 active evaporator at a relatively low value so that the refrigerant vaporizes at low temperature and abstracts heat from the evaporators in a well known manner.

50 The foregoing defines a conventional refrigerating system having a pair of flooded evaporators operating at different temperatures and connected to a common condensing unit in such manner that they are selectively operated. Our improved control apparatus will now be applied to 55

this system. It is to be understood that the system disclosed is shown by way of example and that our improved control apparatus may be applied to other two-temperature systems having either flooded or so-called dry type evaporators with means for effecting vaporization in the evaporators, selectively.

The chamber 11, cooled by the high temperature evaporator 13, is maintained between predetermined temperature limits preferably by means of a gas-type thermostat, generally indicated at 38. The thermostat 38 includes an expansible bellows 39 connected to a bulb 41 by means of a tube 42. As is well understood, thermostats of this type have a volatile fluid contained in the bulb 41, the pressure of which is a function of the temperature of the bulb. Accordingly, the bellows 39 expands and contracts as the evaporator 13 and bulb 41 increase and decrease in temperature, respectively. In this connection, it will be understood that the thermostat 38 may be made responsive to the temperature of the air in the chamber 11 instead of the temperature of the evaporator 13 by disposing the bulb 41 in the air within the chamber 11.

Expansion of the bellows 39 is opposed by a spring 43, the bias of which may be adjusted by an adjusting member 43a, whereby the temperatures at which the thermostat 38 operates is varied. A movable member or arm 44, pivoted at 45, is actuated by the bellows 39 as it expands and contracts and actuates a switch 46 having stationary and movable contact members 47 and 48, respectively. A quick make and break mechanism 49 of any suitable type may be interposed between the switch 46 and the movable member 44. As shown, the quick make and break mechanism 49 includes a pivoted arm 51 carrying the movable contact 48 and connected by a tension spring 52 to the movable arm 44.

As the center of the spring 52 passes upwardly beyond the pivot point of the arm 51 due to expansion of the bellows, the arm 51 is snapped upwardly about its pivot by the tension of the spring 51. Accordingly, the contacts 48 and 47 are engaged and the switch structure 46 is in its closed position. Contraction of the bellows lowers the spring 52 below the pivot point of the arm 51 so that the arm 51 snaps downwardly to open the switch 46. The function of the switch 46 will be referred to in detail hereinafter.

The temperature of the air in the chamber 12 and of the evaporator 14 is controlled by a thermostat, generally indicated at 55, and similar in type to the thermostat 38. The thermostat 55 includes a bellows 56 connected by a tube 57 to a bulb 58 containing volatile fluid and disposed within the chamber 12, preferably in contact with the evaporator 14. Expansion of the bellows 56 is opposed by a spring 56a, the bias of which may be adjusted by an adjusting screw 56b. The thermostat 55 includes a pivoted member or arm 60 actuated by the bellows 56 and operating a switch 59 by means of a quick acting mechanism 61. The switch 59 is opened and closed as the bellows 56 contracts and expands, respectively. The operation of the thermostat 55 is similar to the described operation of the thermostat 38.

The thermostat 38 is adjusted to maintain the temperature of the air within the chamber 11 at a higher value than the temperature maintained in the chamber 12 by the thermostat 55. Both thermostats control the operation of the condensing unit 15 and vaporization of refrigerant in the evaporators 13 and 14 in a selective manner.

In accordance with our invention, the food storage chamber 11 is normally refrigerated in preference to the freezing chamber 12 when both require refrigeration in order to preclude an undue rise in the temperature of the food products in the chamber 11 when a high heat load is impressed upon the low temperature evaporator 14 such as, by placing a relatively large quantity of water in the trays 18 for freezing. There are times, however, when it is desirable to operate the low temperature evaporator for rapidly producing ice cubes or for congealing desserts, and, in order that this operation may be effected, we provide a mechanism for manually adjusting the control, so that the temperature of the low temperature evaporator may be depressed to a relatively low value, after which normal control is established. The manually adjustable mechanism is so arranged that it may be manually rendered inactive prior to the time that normal control is automatically reestablished or, in other words, prior to depressing the temperature to the value at which normal control is automatically established.

The manually actuated mechanism is shown generally at 62 as an accessory to the low temperature thermostat 55 and preferably includes a member 63 pivoted at 64 to a fixed portion of the thermostat structure. A tension spring 65 is attached to the member 63 and to a fixed portion of the thermostat structure 55. The spring 65 defines an accentuating device for biasing the member 63 in an upper or a lower position depending upon whether the center of the spring 65 is above or below the pivot point 64. The pivoted member 63 is manually actuated by a rod 66 having a handle or knob 67, accessible to the operator. The rod 66 preferably carries the movable element of an electric switch 68 that is respectively opened and closed when the rod 66 and the member 63 are in their upper and lower positions.

During periods when the mechanism 62 is inactive, or when the member 63 is in the lower position, the thermostat 55 operates in the manner described for maintaining the evaporator 14 or chamber 12 at the temperature determined by the adjustment 56b. During periods when the evaporator 14 is to be operated in preference to the evaporator 13 or, in other words, during quick freezing operations, the knob 67 is pressed for moving the member 63 upwardly into engagement with the movable arm 60. The arrangement is such that the member 63, when actuated to its upper position, effects sufficient movement of the arm 60 to close the switch 59. As described hereinafter, this operation effects operation of the condensing unit 15 and refrigeration of the chamber 12.

The temperature of the chamber 12 is depressed to a predetermined value preferably lower than the value at which the thermostat 55 normally terminates refrigeration of the chamber 12. This is brought about due to the fact that the spring 65 is above the pivot point 64 and biases the member 63 and the arm 60 upwardly in opposition to the bias of the spring 56a. Accordingly, the temperature and pressure of the fluid in the bulb 58 must be depressed to a lower than normal value before the bellows 56 contracts sufficiently to effect opening of the switch 59, during which operation, the mechanism 62 is returned by the arm 60 to its inactive position or the position shown in the drawing. Closure of the switch 68 reestablishes normal automatic control wherein 75

preference of refrigeration is returned to the high temperature evaporator 13.

The mechanism 62 may be manually returned to its inactive position at any time by manually 5 moving the adjusting knob 67 to the position shown.

The source of power for the motor 17 and solenoid 36 is represented by the line conductor L₁ and L₂. As shown, one terminal of the solenoid 10 36 is connected to the line conductor L₂ and its other terminal is connected by a conductor 71, controlled by the switch 68, to one terminal of the motor 17, the opposite terminal of the motor 17 being connected to the line conductor L₁. The 15 switches 46 and 62 are connected in series in a conductor 72 extending from the line conductor L₂ to the conductor 71 whereby a parallel circuit for the energization of the motor 17 is formed. The parallel circuit including the conductor 72 20 defines a shunt across the solenoid 36 so that it will be apparent that when all switches 46, 59 and 68 are closed, the solenoid 36 is deenergized due to said shunt. This condition prevails during normal automatic operation when both of the 25 chambers 11 and 12 require refrigeration. Accordingly, the valves 34 and 35 are in the position shown so that the evaporator 13 receives refrigerant and the chamber 11 is refrigerated in preference to the chamber 12.

30 Operation

As shown in the drawing, the switches 46 and 59 of the thermostats are open which indicates that neither of the chambers 11 and 12 require 35 refrigeration. Assume a rise in temperature in the chamber 11 to the value at which its thermostat 38 closes the switch 46. The motor 17 is energized by the circuit including line conductor L₂, conductor 72, the closed switches 46 and 68, conductor 71, motor 17 and line conductor L₁. As the solenoid 36 is deenergized the valves 34 and 35 are in the position shown and the suction conduit 28 communicates with the conduit 23. Vaporous refrigerant is withdrawn from the evaporator 13 by the compressor and the float 25 operates to admit condensed refrigerant to the evaporator 13 for vaporization. Refrigeration of the evaporator 13 and chamber 11 is effected as is well understood.

As the temperature of the chamber 11 and evaporator 13 is depressed to the desired value, the thermostat 38 opens the switch 46 and the motor 17 is deenergized. Accordingly, refrigeration of the chamber 11 is terminated.

Assume a rise in temperature in the chamber 55 12 to the value at which the thermostat 55 closes the switch 59. The motor 17 is energized by the circuit including the line conductor L₂, the solenoid 36, conductor 71, and closed switch 59, the motor 17 and line conductor L₁. Energization of the solenoid 36 actuates the valves 34 and 35 upwardly for providing communication between the suction conduit 28 and conduit 24. Accordingly, the motor 17 operates the condensing unit 15 to circulate refrigerant through the evaporator 14 until the temperature thereof is depressed to the value at which the thermostat 55 opens its switch 59 for terminating operation of the condensing unit 15.

Assume now that both chambers 11 and 12 require refrigeration and that the thermostatic switches 46 and 59 are closed, the motor 17 is energized by the circuit including conductor 72 and switches 46 and 68. The solenoid 36 is deenergized because of the shunt formed thereacross by

the conductor 72 and the closed switches 46 and 68. Accordingly, the conduits 28 and 33 are communicating and refrigerant circulated by the condensing unit 15 is vaporized in the evaporator 13 for refrigerating the chamber 11. 5

It will now be assumed that the operator manually actuates the mechanism 62 to its active position wherein the member 63 engages the arm 60, as described heretofore. The switch 68 is opened and the shunt circuit referred to in the foregoing is opened. As the switch 59 is closed the motor 17 and solenoid are energized for the circulation of refrigerant through the low temperature evaporator 14. As the conductor 72 is opened by the switch 68, it will be apparent that the switch 46 is ineffective to control the motor 17. Accordingly, refrigeration of the low temperature chamber 12 progresses until the temperature therein is reduced to the value at which the thermostat 55 operates to open the switch 59 20 and to close the switch 68 as described heretofore. Closure of the switch 68 reestablishes normal automatic control of refrigeration of the chambers wherein the higher temperature chamber 11 receives refrigeration in preference to the lower 25 temperature chamber 12 when both demand refrigeration.

From the foregoing it will be apparent that we have provided an improved control system for a two-temperature refrigerator wherein the food 30 storage and low temperature zones thereof are maintained at relatively high and low temperatures, respectively, wherein the food storage zone is refrigerated in preference to the low temperature zone during normal operation with provisions for manually effecting refrigeration of the 35 low temperature zone in preference to the higher temperature food storage zone and wherein normal automatic operation is reestablished manually or automatically when the temperature of 40 the lower temperature zone has been depressed to a predetermined value.

While we have shown our improved control system applied to a refrigerating system of the compressor-condenser-expander type it will be understood that it is equally applicable to other forms of refrigerating systems. Furthermore, it will be understood that the controlling instruments per se which we have employed have been shown by way of example and that other types of controlling instruments may be used. 50

While we have shown our invention in but one form, it will be obvious to those skilled in the art that it is not so limited, but is susceptible of various changes and modifications without departing 55 from the spirit thereof, and we desire, therefore, that only such limitations shall be placed thereupon as are imposed by the prior art or as are specifically set forth in the appended claims. 60

What we claim is:

1. The method of controlling the operation of a refrigerating machine having relatively high and low temperature evaporators, which comprises automatically and selectively effecting refrigeration by the low and higher temperature 65 evaporators in response to demands for cooling thereon and in such manner that the higher temperature evaporator preferentially effects refrigeration when there is a cooling demand on both evaporators, manually effecting refrigeration by the low temperature evaporator in preference to the higher temperature evaporator, at will, and re-establishing automatic control of the evaporators in response to a predetermined 70 low temperature of the low temperature evapo- 75

rator subsequent to an operation thereof that was manually effected.

2. The method of controlling the operation of a refrigerating machine having relatively high and low temperature evaporators, which comprises automatically and selectively effecting refrigeration by the low and higher temperature evaporators in response to demands for cooling thereon and in such manner that the higher temperature evaporator preferentially effects refrigeration when there is a cooling demand on both evaporators, manually effecting refrigeration by the low temperature evaporator in preference to the higher temperature evaporator at will, and establishing automatic control of the evaporators manually, or automatically in response to a predetermined low temperature of the low temperature evaporator subsequent to an operation thereof that was manually effected.
- 10 3. In apparatus for controlling the operation of a refrigerating system having first and second zones to be refrigerated, the combination of first means responsive to the temperature in the first zone for controlling refrigeration thereof, second means responsive to the temperature of the second zone for controlling refrigeration of the second zone, said first and second temperature responsive means being so arranged that refrigeration of the first zone is effected in preference to the second zone when both require refrigeration, and means manually operated at will, to a position wherein refrigeration of the second zone is effected in preference to the first zone, said manually operated means being movable automatically or manually to a second position in which automatic control of refrigeration of both zones is returned to said first and second temperature responsive means.
- 20 4. The combination as claimed in claim 3 wherein said temperature responsive means are provided with adjusting means for varying the temperatures at which they operate.
- 25 5. In apparatus for controlling the operation of a refrigerating system having relatively high and low temperature zones to be refrigerated, the combination of means responsive to predetermined high and low temperatures in the high temperature zone for, respectively, initiating and terminating refrigeration thereof, means responsive to predetermined high and low temperatures in the low temperature zone for respectively initiating and terminating refrigeration thereof, means for selectively effecting refrigeration of the higher temperature zone in preference to the low temperature zone when both require refrigeration, means manually operable at

will, for effecting refrigeration of the low temperature zone in preference to the higher temperature zone, and means responsive to a predetermined low temperature in the low temperature zone for rendering said manually operable means inactive, whereby automatic control of refrigeration of the zones is returned to the two first-mentioned temperature responsive means.

6. In apparatus for controlling the operation of a refrigerating system having high and low temperature zones to be refrigerated, the combination of relatively high and low temperature evaporators for refrigerating the respective high and low temperature zones, means for selectively circulating refrigerant through the evaporators, a first thermostat responsive to the temperature within the high temperature zone for controlling the circulation of refrigerant through its respective evaporator, a second thermostat responsive to the temperature within the low temperature zone for controlling the circulation of refrigerant through the low temperature evaporator, said thermostats being so constructed and arranged that during normal operation, the second thermostat is rendered inactive when the first thermostat operates to effect circulation of refrigerant through the high temperature evaporator, means for manually adjusting said second thermostat so that it effects circulation of refrigerant through the low temperature evaporator and whereby the first thermostat is rendered inactive and means for rendering the manually adjusting means inactive and for reestablishing normal control by the thermostats in response to a predetermined low temperature within the low temperature zone.

7. The method of controlling the operation of a refrigerating machine having relatively high and low temperature evaporators, which method comprises normally effecting selective refrigeration by the low and high temperature evaporators in response to demands for cooling thereon and in such manner that the high temperature evaporator preferentially effects refrigeration when there is a cooling demand on both evaporators, manually effecting refrigeration by the low temperature evaporator in preference to the high temperature evaporator at will and reestablishing normal control of the evaporator in response to a predetermined low temperature of the low temperature evaporator subsequent to an operation thereof that was manually effected.
